CARTRIDGE CASE TRIMMER OR THE LIKE

John Kaupp, Sheridan, Colo., assignor to Black Tool,
Inc., Denver, Colo., a corporation of Colorado

Filed July 21, 1958, Ser. No. 51,855

Term of patent 7 years

(Cl. D54—14)

FIG. 1.

FIG. 2.

FIG. 3.

FIG. 4.

Fig. 1 is a side perspective view of a cartridge case trimmer embodying my new design;

Fig. 2 is a front elevation thereof;

Fig. 3 is a rear elevation thereof; and

Fig. 4 is a top plan view thereof.

The essential features of my design are shown in full lines. The dotted lines showing the nonessential features of Fig. 1 have been omitted in Figs. 2, 3 and 4 for convenience of illustration.

I claim:

The ornamental design for a cartridge case trimmer or the like, as shown and described.
